ATTORNEY.

UNITED STATES PATENT OFFICE.

ARTHUR W. HUTCHINS, OF CRANSTON, RHODE ISLAND, ASSIGNOR OF ONE-HALF TO
WILLIAM ELY, OF PROVIDENCE, RHODE ISLAND.

MEANS FOR DRYING ARTICLES OF JEWELRY.

1,075,476.

Specification of Letters Patent.

Patented Oct. 14, 1913.

Application filed November 23, 1910. Serial No. 593,829.

To all whom it may concern:

Be it known that I, ARTHUR W. HUTCHINS, of the city of Cranston, county of Providence, and State of Rhode Island, have invented certain new and useful Improvements in Means for Drying Articles of Jewelry; and I do hereby declare the following specification, taken in connection with the accompanying drawings, forming a part 10 of the same, to be a full, clear, and exact description thereof.

The invention relates to an improved form of air blast drying machine of the character employed in drying articles of jewelry, and 15 has for its principal object to produce a machine of this character which is simpler in construction and more efficient in its operation than any machine of this character heretofore produced.

20 A further object of the invention is to provide a container for machines of this character which is adapted to be manually held or guided and which will hold articles of jewelry of various sizes and shapes separate from each other.

Another object of the invention consists in providing a swinging support for the container.

Another object of the invention consists 30 in providing a drying machine with a plurality of containers and a movable support for each of said containers.

To these ends the invention consists in the novel construction and arrangement of 35 the container shown and described in the accompanying specification and more specially set forth in the claims.

In describing the invention in detail reference will be made to the accompanying 40 drawings, in which—

Figure 1 is a side elevation of my novel form of container held in the hand of the operator and having a portion of the side broken away. Fig. 2 is a top plan view of 45 the same. Fig. 3 is a side elevation in partial section and on a reduced scale of an air-blast drying machine embodying my invention. Fig. 4 is a top plan view of a modified construction showing a plurality 50 of containers. Fig. 5 is a side elevation of the container in operation.

55 Referring to the drawings, the container 1 comprises an open mesh woven wire body portion which is mounted to revolve on a post 2 extending centrally therethrough.

The post 2 is mounted in suitable bearings 3 and 4 formed at the axis of the radially extending ribs 5 and 6 at the top and bottom of the container, as shown in Fig. 1. Said post 2 is provided with a suitable operating 60 handle 7.

To the upper rim of the container is rigidly secured an annular ring 8 which is provided with a series of outwardly extending inclined blades 9 around the outer periphery 65 thereof. The annular ring 8 is also provided with a series of hooks 10 around the outer periphery and the ribs 5 are provided with upright posts 11 having forked ends 12, for purposes to be hereinafter referred to. 70

In Fig. 3, which shows an improved form of air-blast drying machine, 13 represents a heating chamber provided with a coil of steam-pipes 13' arranged to be connected to a steam supply. Removably mounted above 75 the heating chamber 13 is a drying receptacle 14 having a perforated bottom 15 and an open top. An exhaust blower 16 is connected to the heating chamber 13 and an air-blast pipe 17 extends upward from the 80 blower 16 and terminates in a downwardly extending nozzle 18 which is centrally located above the drying receptacle 14. If desired a valve or gate 17' may be employed 85 for controlling the flow of air.

I prefer to use a support or standard 19 for my novel container which is arranged and adapted to be placed upon the perforated bottom 15 of the drying receptacle 14 and which carries a bracket 20 pivotally 90 mounted thereon. The bracket 20 has a recess 21 in its free end to receive an extension 22 on the lower end of post 2. Said bracket 20 is also provided with an arm 23 extending upwardly and outwardly and provided 95 with a slotted end 24 in vertical alinement with the recess 21, all as shown in Fig. 3. The slotted end 24 is preferably provided with a latch member 24' for closing said slotted end, as shown in Figs. 3 and 4. 100

The operation of the device is as follows: Certain articles of jewelry such as bracelets 25 are suspended from the forked ends 12 of the posts 11, articles such as lockets 26 are hung on the hooks 10, and various small 105 articles 27 are placed upon the interior of the container, as shown in Fig. 1. Said container is then preferably mounted in the bracket 20 and forked end 24 of the arm 23, as shown in Fig. 3. The operator retains 110

hold of the handle 7 and now gradually swings the bracket 20 until a portion of the inclined blades 9 are beneath the open end of the nozzle 18, so that the continuous currents of heated air flowing therefrom will impinge upon said inclined blades 9 and cause the container to rotate at a high rate of speed in the direction of the arrow, as shown in Fig. 2. The centrifugal force induced thereby causes the bracelets 25 and the lockets 26 to swing outward, as shown in Fig. 5, and acts to throw off any drops of liquid that may be on the articles, while the heat is free to pass all around the articles and quickly absorbs the remaining moisture. If desired the standard 19 may be omitted and the container held in position beneath the nozzle 18 by the hand of the operator, as shown in Fig. 5.

Fig. 4 shows a modified form in which the standard 19 carries two swinging brackets 20, connected together and each having a container mounted thereon. With this arrangement one of the containers is in operative position while the other is in inoperative position, and a movement of the one which is in inoperative position to operative position will simultaneously move the container which is in operative position to inoperative position. Thus one container can be emptied and refilled while the articles in the other container are going through the drying operation, thereby saving a great deal of time and doubling the capacity of the machine.

What I claim as my invention and desire to secure by Letters Patent is:

1. An article of the character described comprising a central post provided with a suitable handle, a woven wire body portion mounted to revolve upon said post, a series of inclined blades upon the exterior of said body portion, a series of posts and a series of hooks upon said body portion arranged and adapted to hold articles of jewelry.
2. The combination, with an air blast drying machine, of a plurality of containers for holding articles of jewelry mounted to revolve therein and means for moving said containers to operative and inoperative positions.
3. The combination, with the drying

chamber of an air blast drying machine, of two containers mounted to revolve therein, means for moving each of said containers to operative and inoperative positions, one of said containers being arranged and adapted to be in operative position while the other container is in inoperative position.

4. The combination, with the drying chamber of an air blast drying machine, of a standard mounted therein, a movable bracket mounted on said standard, and a revolving container removably mounted in said bracket.

5. The combination, with the drying chamber of an air blast drying machine, of a removable standard mounted therein, two movable brackets mounted on said standard, and a container mounted to revolve on each of said brackets.

6. The combination, with the drying chamber of an air blast drying machine, of a movable bracket pivoted at one end and provided with an opening in its free end, an arm extending upward and outward from said bracket and provided with a slot at its free end, means for closing said slot, and a removable container mounted to revolve in said opening and slot respectively.

7. In an article of the character described, the combination of a heating chamber, a drying receptacle located above and outside of said heating chamber, a blower, a pipe connecting the heating chamber with the blower, and a pipe connected with the blower and having its open end located above and adjacent to the top of said drying receptacle.

8. In an article of the character described, the combination of a heating chamber, a removable drying receptacle located above said heating chamber and having a perforated bottom which forms the top of said heating chamber, a blower, a pipe connecting the heating chamber with the blower, and a pipe connected with the blower and having its open free end located above and in close proximity to said drying receptacle.

ARTHUR W. HUTCHINS.
